CHRIS KREI AND FRED KREI, OF SAMOA, CALIFORNIA

FIRE KINDLER

Application filed April 7, 1928. Serial No. 268,254.

The present invention relates to improvements in fire kindlers, and has for its principal object to provide, as an improved article of manufacture, a fire kindler that will, at all times, be positive and efficient in carrying out the purposes for which it is designed.

One of the important objects of the present invention is to provide a fire kindler which will eliminate the necessity of having to start a fire, in a stove, fire-place or furnace, with paper, shavings, or other combustible material.

A still further object is to provide a fire kindler, which is simple in construction, inexpensive, strong and durable, and further well adapted to the purpose for which it is designed.

Other objects of the invention will become apparent as the nature of the invention proceeds and when taken in connection with the accompanying drawing.

In the accompanying drawing, forming a part of this application, and in which like numerals designate like parts throughout the several views;

Figure 1 is a detail perspective view of the wax covered piece of fabric that forms an important part of the present invention.

Figure 2 is a side elevation of the piece of burlap wrapped spirally and confined within a binder of wax paper, the latter being shown in section.

Figure 3 is a sectional view, taken approximately on the line 3-3 of Figure 2, and

Figure 4 is a detail perspective view of the fire kindler per se.

In the drawing, wherein for the purpose of illustration is shown the preferred embodiment of my invention, the numeral 1 designates a rectangular shaped piece of burlap that is coated on both sides with paraffin wax. This burlap piece of material is reduced to a spiral body as is clearly shown in Figures 2 and 4 of the drawing. The wax paper which is rolled around the burlap body extends beyond the ends of the spirally wrapped body, and the ends of this wax binder are twisted as shown at 3 in Figure 4, whereby either end of the wax

paper may be readily ignited with a match and the entire fire kindler placed in a stove, fire place or furnace, in which wood or other fuel has been previously placed. The twisted ends 3 further tend to fasten the 55 wrapper or binder in place. As the paper binder and the burlap body are both coated with paraffin wax, the same are rendered highly inflammable, thus producing a flame which will ignite fuel and the wax will 60 melt and run off into the fuel to further insure proper ignition of the fuel.

By providing a fire kindler of this character, the use of paper, shavings or other combustible material, used as a fire kindler 65 will be eliminated. The simplicity of our fire kindler enables the same to be manufactured at a very low cost.

While we have shown the preferred embodiment of our invention, it is to be understood that minor changes in size, shape, and arrangement of parts may be resorted to, without departing from the spirit of the invention and the scope of the appended 70 claims.

Having thus described our invention, what we claim as new is:

1. A fire kindler of the class described comprising a piece of burlap coated on both sides with paraffin wax, said fabric being wound into a spiral body, a binder of wax paper wrapped around the spirally wound body of burlap, the ends of the binder extending beyond the respective ends of the spirally wound body, the ends of the binder 80 being twisted.

2. A fire kindler comprising a piece of burlap coated with paraffine wax, said piece of burlap being reduced to a spiral body, and an inflammable covering enclosing and 85 secured on the body of burlap.

In testimony whereof we affix our signatures.

CHRIS KREI. 95
FRED KREI.
